UNITED STATES PATENT OFFICE.

JOHN ANTHONY ROWE, OF LONDON, ENGLAND.

APPARATUS FOR AUTOMATICALLY DISCHARGING GUNS OF WAR-SHIPS.

SPECIFICATION forming part of Letters Patent No. 629,819, dated August 1, 1899.

Application filed March 28, 1899. Serial No. 710,795. (No model.)

To all whom it may concern:

Be it known that I, JOHN ANTHONY ROWE, of 68 Hampton road, Forest Gate, London, England, have invented certain new and useful Improvements in Apparatus for Automatically Discharging the Guns of War-Ships while the Vessels are Laboring Among Waves, of which the following is a specification.

This invention relates to apparatus for enabling the guns of a war-ship rolling and pitching among the waves of the sea to be accurately and automatically discharged at the moment when the war-ship is upright or at any desired predetermined angle from the upright position.

According to this invention the guns are fired by means of an electric current passing in a circuit which is normally open, but which is closed by the operation of the apparatus when the ship is upright or, if desired, when the ship has reached a predetermined angle in its rolling movement.

In the accompanying drawings, Figure 1 is a central longitudinal vertical section illustrating an apparatus constructed in accordance with the preferred manner of carrying out the invention. Fig. 2 is a vertical cross-section on the line II II of Fig. 1. Fig. 3 is a vertical cross-section on the line III III of Fig. 1, looking toward the right-hand end of that figure. In Fig. 3 a gun is shown in side elevation on a considerably smaller scale. Fig. 4 illustrates a portion of Fig. 1 on a larger scale.

1 is a cylindrical submerged float arranged with its axis lying horizontally in the liquid 2 contained in a cylindrical casing 2, which is also situated with its axis lying horizontally. The float 1 and its containing casing 2 do not bear against each other at any part. The casing 2 is fitted at each of its ends with a cover 3, formed with a central aperture 4, through which extends a spindle 5, projecting from the corresponding end of the float. There is no contact between the spindles 5 and the sides of the apertures 4 in the end covers 3. (See Fig. 4.)

The liquid 2, in which the float 1 is submerged and which is preferably a practically non-freezing liquid, such as a solution of chlorid of calcium in water or other suitable solution, completely fills up the casing 2. It

is prevented from escaping through the aforesaid central aperture 4 in the covers 3 by means of sleeves 6, of rubber or other suitable flexible material which is impervious to water and which will allow of the float 1 and casing 2 oscillating to and fro relatively to each other on each side of the vertical. The sleeves 6 are attached at each end in a watertight manner respectively to the cover 3 and the spindle 5.

7 is a light net of suitable material fitted over each rubber sleeve 6 to prevent undue expansion arising from internal pressure. On each spindle 5, at or near its end, there is fixed a disk 8, to the lower part of which is fitted a small weight 9, which, with other considerations, serves to determine or regulate the period of oscillation of the float 1.

The weight of the float 1 and its attachments is made exactly equal to the weight of the liquid displaced by it, and in order to maintain this equality the temperature of the liquid should be kept constant, or where this is inconvenient the desired equality can be maintained by placing a greater or less number of removable disks or weights on the spindles 5. The center of gravity of the float and its attachments is arranged to be slightly below the geometrical center of the float, the exact position of the said center of gravity being determined by the total weight of the float, the amount of the small weight 9 above referred to, and the distance of said weight 9 from the center of the spindle. Instead of employing a weight 9, as above described, the same object can be attained by forming a hole or recess in the disk at the upper part of same.

The casing 2 is carried on feet 10, fixed to the deck 11 or other suitable part of the war-ship and so that the float-spindles 5 lie fore and aft of the ship when the apparatus is intended to fire the broadside guns. When the apparatus is to be used for firing the bow or stern guns, it must be arranged with the float-spindles 5 lying athwartships, so as to be operated by the pitching of the ship.

A pipe 12, formed with an expansion-chamber 12^a, is provided for filling the casing 2, and an aperture 13, normally closed by a screw-plug 13^a, serves for the purpose of emptying said casing.

The float 1 being accurately balanced in the liquid 2^a in the casing 2 does not require any support; but in order to secure accurate adjustment of the parts center holes 5^a are formed in the ends of the spindles 5, into which fit centers 14 14, carried by strong brackets 15, fixed to the ship's deck 11, as shown, or to a suitable overhead frame. There is not necessarily contact between the centers 14 and the spindles 5. Their use is to adjust the parts, and after the adjustment has been effected the centers 14 14 are preferably moved back by means of the screws 14^a to the extent of, say, one thirty-second of an inch.

On each head center 14 there is fitted an adjustable disk 16, adapted to be turned by hand through a suitable angle and to which is connected an insulated wire 17, leading from one terminal of an electric battery X. Similarly, another insulated wire 18, leading from the other pole of the said battery, is attached to the disk 8, above described as being fixed to the float-spindle 5. The wires 17 and 18 are not in metallic connection with the disks. 19 and 20 are projections or contacts carried, respectively, by the two disks 8 and 16. They are insulated from the disks 8 and 16 by means of pieces of non-conducting material 19^a and 20^a, respectively, (or the disks may be made of insulating material, such as ebonite,) but are in metallic contact with the wires 18 and 17, respectively. They face each other in such relative positions that so long as the ship is rolling or pitching at an angle with the vertical the said contacts 19 20 will be situated apart and the battery-circuit 17 18 will remain open; but as soon as the ship assumes an upright position the contacts 19 20 will touch each other and by closing the battery-circuit 17 18 will fire the gun or guns included in the said circuit.

In a ship fitted with broadside guns the battery-wires 17 and 18 at one end of the apparatus will discharge the starboard broadside and the battery-wires at the other end the port broadside. The wires 17 and 18 are shown at only one end of the apparatus.

If it is desired to keep the gun or guns in the horizontal still-water position and to fire them when the requisite elevation or depression for the range is obtained by the inclination of a rolling or pitching ship, as illustrated by Fig. 3, the adjustable disk 16 is shifted around through the requisite angle of elevation or depression, which can be read from a suitable scale 21, affixed to the supporting-bracket 15. Then on said disk 16 being fixed temporarily in place at said angle by means of a set-screw 22 or the like contact between the projections 19 20 on the disks 8 and 16 does not take place when the ship is upright, but when the axis of the gun 23 is at a predetermined angle above or below its normal horizontal level. For example, if it be desired to discharge the gun 23 (which has been laid horizontally along the

line A A when the ship was upright) automatically by means of this apparatus when the gun is at an angle α —say ten degrees, as shown in Fig. 3—the disk 16 must be turned through the angle α (ten degrees) and fixed in this position. Then when the gun is caused by the rolling or pitching of the ship to coincide with the line B B the gun will be discharged.

Instead of the wires 17 18 being connected, respectively, with the disks 16 and 8 they may be connected to any other suitable parts so long as they cause the circuit to be closed when the ship is upright or reaches a predetermined angle.

When the apparatus is intended to effect the discharge of an all-around-firing gun or of a turret-gun, the apparatus must be moved synchronously with the revolving gun platform or turret. In such cases the entire apparatus is rigidly secured to a bed-plate, from which projects a vertical spindle, by means of which revolving or oscillating motion can be given to the apparatus in an automatic manner by leading an endless chain over two similar wheels, one on the spindle of the bed-plate and the other on a spindle of the gun platform or turret, or by leading an endless rope over two similar pulleys, or by a control-shaft united by tooth-wheels on both spindles, or by other simple means.

What I claim, and desire to secure by Letters Patent, is—

1. In apparatus for automatically discharging the guns of a war-ship by means of an electric current passing in a circuit in which the guns are included, a cylindrical float submerged in a casing fixed to part of the ship, said float and its attachments being equal to the weight of the liquid displaced by it and said float having spindles passing in a watertight manner through the ends of said casing, in combination with means connected with said spindles and operated by the angular change in the relative positions of said float and said casing to manipulate the electric circuit and thereby fire the guns included in said circuit when the ship is upright or reaches a predetermined angle, substantially as set forth.

2. In apparatus for automatically discharging the guns of a war-ship by means of an electric current passing in a circuit in which the guns are included and which is normally open but which is closed to fire the guns when the war-ship is upright or in a predetermined position relatively to the horizontal, the combination of a casing fixed to a ship and having coaxial apertures in two opposite vertical ends, liquid filling said casing, a cylindrical float submerged horizontally in said liquid having two coaxial horizontal spindles projecting respectively from its said vertical ends through said coaxial apertures without touching same, means for preventing the liquid from escaping through said coaxial apertures, and means operated by the angular

change in the relative position of said float and said casing to close the electric circuit and thereby fire the guns included in said circuit, substantially as specified.

- 5 3. In apparatus for automatically discharging the guns of a war-ship by means of an electric current passing in a circuit in which the guns are included and which is normally open and which fires the guns when closed,
10 the combination of a casing fixed to the ship's deck and having coaxial apertures in two opposite vertical ends, liquid filling said casing, a cylindrical float submerged horizontally in said liquid having two coaxial horizontal
15 spindles projecting respectively from its said vertical ends through said coaxial apertures without touching same, means for preventing the liquid from escaping through said coaxial apertures, disks mounted on the float-

spindles and weighted so as to determine the 20 period of oscillation of the float, disks adjustably fixed relatively to the ship's deck, electric contacts mounted respectively on the float-spindle disks and the adjustably-fixed disks and arranged to be in contact with each other 25 in the predetermined firing position of the ship's guns, and wires forming part of the electric circuit for firing the guns and connected respectively to said electric contacts, substantially as specified. 30

In witness whereof I have hereunto signed my name in the presence of two subscribing witnesses.
